H. P. BALL AND A. L. GRAVES, OF ALBANY, NEW YORK.

Letters Patent No. 61,597, dated January 29, 1867.

IMPROVED SHEARS.

The Schedule referred to in these Letters Patent and making part of the same.

TO ALL WHOM IT MAY CONCERN:

Be it known that H. P. BALL and A. L. GRAVES, of Albany, in the county of Albany, and in the State of New York, have invented a new and useful improvement in "Shears;" and do hereby declare that the following is a full, clear, and exact description thereof, reference being had to the accompanying drawings, and to the letters of reference marked thereon.

In the annexed drawings, making part of this specification, A A represent the handles of the shears, pivoted together at *g*, with the jaws B B formed on their forward ends. These handles with jaws formed upon them are made of malleable iron, or any other suitable material. The inner faces of the jaws B B are provided with recesses, into which are fitted the steel blades or knives C C. These knives have cutting edges, and are pivoted to the jaws B B near their forward ends by means of screws at *e e*. The heels of these knives are stationed at any desired point, or moved by means of set-screws *d d* which act against their back edges. The inner ends of the knives C C are bevelled, as seen, from *x* to *x*, so that when a screw is inserted in the jaw, as seen at *a*, the under side of the screw-head will fit the bevel of the knife. The screws *a a* are for the purpose of stationing the knives or blades at their rear ends. It will readily be seen that by this arrangement and construction the blades C C may be adjusted upon the jaws as fast as said blades wear away on their cutting edges by use. To change or adjust the blade, the screws *a a* are loosened, and the set-screws *d d* turned forward as far as it is desired to set the said blades up at their heels. The screws *a a* are then tightened again, and the blades are held fast in the desired position. When the knives or blades wear out the old ones can be replaced by new ones.

Having thus fully described our invention, what we claim as new, and desire to secure by Letters Patent, is—

Adjusting the knives or blades C C upon the jaws B B of the shears, substantially in the manner and for the purpose herein specified.

In testimony that we claim the foregoing, we have hereunto set our hands and seals this 15th day of October, 1866.

H. P. BALL,
A. L. GRAVES.
